UNITED STATES PATENT OFFICE.

SAMUEL W. TATE, OF PARMA, IDAHO.

WOVEN-WIRE-FENCE-FABRIC STRETCHER.

1,139,238.

Specification of Letters Patent.

Patented May 11, 1915.

Application filed September 10, 1913. Serial No. 789,120.

To all whom it may concern:

Be it known that I, SAMUEL W. TATE, a citizen of the United States, residing at Parma, in the county of Canyon and State 5 of Idaho, have invented a new and useful Woven - Wire - Fence - Fabric Stretcher, of which the following is a specification.

The device forming the subject matter of this application is a stretcher, adapted to be 10 employed in tightening wire fences, and one object of the invention is to provide a stretcher which may be manipulated to cause the wire fence to extend past the post which constitutes a fulcrum for the stretcher, so 15 that the constituent wire of the fence may be stapled down upon said post.

With the above and other objects in view which will appear as the description proceeds, the invention resides in the combination 20 and arrangement of parts and in the details of construction hereinafter described and claimed, it being understood that changes in the precise embodiment of the invention herein disclosed can be made without 25 in the scope of what is claimed without departing from the spirit of the invention.

In the drawings:—Figure 1 shows the invention in top plan; Fig. 2 is a top plan of the invention, Fig. 2 depicting the stretching mechanism in a different position from that shown in Fig. 1; Fig. 3 is an enlarged top plan of the stretching mechanism, the clamp being turned at an angle of 90° from its normal position; Fig. 4 is a perspective 30 of the socket which constitutes a part of the wire stretching mechanism; Fig. 5 is a side elevation of the operating lever, parts being broken away; Fig. 6 is a top plan of the lever; Fig. 7 is a sectional detail showing a 35 modification; Fig. 8 is a perspective showing an anti-friction bearing which is employed.

The wire stretcher comprises an inner tube 20, to one end of which is secured a socket 25 19 having a transverse head 18 provided with openings in which the ends of the chains 17 are secured, the latter being connected with a clamp 1. As shown in Fig. 7, tube 20 may be reinforced by a supplemental tube 20'. The inner tube 20 is mounted to slide in a cap 21, provided with a bead 22, the cap 21 being mounted upon one end of an outer tube 23 which receives the inner tube 20 slidably. Threaded or otherwise secured 50 in the inner end of the inner tube 20 and located within the outer tube 23 ad-

jacent the rear end thereof is a socket 24. A cap 25 is secured to the rear end of the outer tube 23. Threaded into the socket 24 and lying within inner tube 20 is a screw 26 60 provided adjacent its rear end with an abutment 27. If desired, rollers 28 may be inserted between the abutment 27 and the cap 25. The exposed rear end of the screw 26 is threaded to receive superposed nuts 29 65 lying outside of the cap, and the extreme end of the screw 26 is squared as indicated at 30, to receive an actuating crank which will be described hereinafter in detail.

Surrounding the outer tube 23 is a split 70 collar 31 held in place by a bolt 32 and abutting against the cap 21. The bolt 32 serves as a mounting for a prong 33 provided with a chain receiving finger 34, the prong 33 including an extended foot 35 having a notch 36 which fits over the bead 22 of the cap 21. Obviously, if desired, the prong 33 may be mounted in place upon the outer tube 23 in any desired manner, the showing of the drawings in this regard 75 being typical merely.

Mounted to slide along the outer tube 23 is a ring 37 with which is connected a chain 38. The ring 37 may be held in adjusted positions along the tube 23, through the 80 medium of the studs 39 which project from the tube.

An actuating lever is shown in Figs. 5 and 6 and may be of any desired form. The lever, denoted generally by the numeral 40 90 is a composite structure and comprises a bar 41 provided at one end with a handle 42. Plates 43 are united with the other end of the bar 41 by means of securing elements 44. A ratchet wheel 45 is provided, the same 95 being equipped with circular trunnions 46, journaled for rotation in openings in the side plates 43. The ratchet wheel 45 is equipped with a squared opening 47. Resilient pawls 48 are secured as indicated at 100 49 to the edges of the bar 41, the extremities of the pawls 48 being adapted, respectively, to coact with the ratchet wheel 45. In the inner edges of the pawls 48 there are notches 50 adapted to be engaged successively by a dog 51 which is journaled in the bar 41 and in one of the side plates 43. The dog 51 includes an exposed finger piece 52, whereby the dog may be rotated.

The practical operation of the device 110 hereinbefore described, may be carried out in a variety of ways, but the following steps

illustrate one mode of operating the structure. The squared end 30 of the screw 26 is engaged in the opening 47 in the ratchet wheel 45, the lever 40 being thus mounted in place on the end of the screw. By manipulating the dog 51 through the medium of the finger piece 52, the end of the dog may be engaged in the notch 50 of one spring pawl 48, holding the said pawl out of engagement with the ratchet wheel 45, the other pawl being engaged with the ratchet wheel. Obviously, the function of the dog 51 is to permit the spring pawls 48, respectively, to be engaged with the ratchet wheel 45, depending upon the direction of rotation which is to be imparted to the screw 26. The lever 41, through the medium of the handle 42 may be used to impart continuous rotary movement to the screw 26, or, if desired, by manipulating the pawls 48 through the medium of the lever, the latter may be employed to impart a step-by-step rotary movement to the screw 26.

In Figs. 1 and 2, a fence post is shown at 25 53, the numeral 54 indicating a brace for the fence post. The brace 54 may or may not be present, but it has been shown in the drawings, in order that different positions of the stretcher, as shown in Figs. 1 and 2 30 with respect to the fence post may be more clearly understood.

The ring 37 is slid forward along the outer tube 23 and is held in place between certain of the studs 39. The chain 38 is passed around the post 53 and is engaged with the finger 34 on the prong 33, to hold the prong adjacent the post 53, as shown in Fig. 1. The screw 26 is actuated by the lever 40, the screw serving to advance the inner tube 20 until the same protrudes beyond the end of the outer tube 23 as shown in Fig. 1. The wire fence which is to be stretched, indicated at 55, is engaged with the clamp 1.

45 The screw 26 may be rotated through the medium of the lever 40 until the inner tube 20 is telescoped within the outer tube 23. Then, the post 53 is used as a fulcrum, the tubes 20 and 23 being employed as a lever, 50 this lever being swung around the post 53 until the lever assumes the position shown in Fig. 2. The prong 33, under the tension of the wire fence 55 will be embedded in the post 53, as shown in Fig. 2. Then, the chain 55 38 is disengaged from the finger 34 and the ring 37 is slid along the outer tube 23 until the ring is in a position adjacent the free end of the outer tube, as shown in Fig. 2. The chain 38 is passed through the wire 60 fence 55 and is engaged in a loop 56, around a bar 57 which is placed in abutment with the wire fence 55. Then, the screw 26 may be actuated by the medium of the crank or lever 40 to advance the inner tube 20 out of 65 the outer tube 23 in the direction of the ar-

row A in Fig. 2. As the stretching operation proceeds, the collar 37 is pushed forward manually, to keep the collar opposite to the bar 57, thus preventing the collar from binding on the outer tube. The end 70 of the wire fence will finally be carried past the post 53 and may be stapled thereto, as indicated at 58.

In Fig. 1, the inner tube 20 is shown as extended beyond the outer tube 23, at the 75 inception of the stretching operation. This step in the operation need be resorted to only when there is a considerable amount of slack in the wire fence 55. If a short length of fence is being stretched, or if there is but 80 little slack in the fence, the tube 20 will be telescoped within the tube 23 in the first instance, the initial step in the stretching operation consisting in swinging the telescoped tubes around the post 53, from the position 85 shown in Fig. 1 to the position shown in Fig. 2.

The abutment 27 which constitutes a part of the screw 26 exercises its function when the tube 20 is being moved out of the tube 90 23, the superposed nuts 29 exercising their function when the tube 20 is being retracted into the tube 23.

The construction of the stretcher portion of the invention is such that, by a simple operation, the wire fence may be advanced beyond the stretching post, and be stapled thereto.

Having thus described the invention, what 100 is claimed is:—

1. A wire fence stretcher comprising a pair of members united for relative longitudinal movement; means for producing relative longitudinal movement between said members; support engaging means on one 105 member, whereby both members may be employed as a lever, one portion of said means being movable for assembly with a fence, at the completion of the lever-wise operation of the stretcher and being slidable along 110 said member for assembly with the fence.

2. A wire fence stretcher comprising an inner tube; wire holding means assembled therewith; an outer tube in which the inner tube slides; a screw threaded into the inner 115 tube and held for rotation but against longitudinal movement in the outer tube; a support-engaging projection on the outer tube; and a flexible element detachably secured at one end to the projection, the other 120 end of the flexible element being slidable along the outer tube.

3. A wire stretcher embodying a main member; an auxiliary member mounted to move in the main member; a wire holder 125 on the auxiliary member and located beyond one end of the main member; operating means connecting the main and auxiliary members and adapted to retract the auxiliary member and the wire holder, the operat- 130

ing means being reversible to advance the auxiliary member and the wire holder; and spaced lateral elements on the main member adapted to coöperate with a suitable support to permit an end for end reversal of the stretcher and to permit the stretcher to be employed as a lever, intermediate the retraction and the advancement of the auxiliary member, said elements, respectively, affecting a thrust bearing, during the retrac-

tion and the advancement of the auxiliary member.

In testimony that I claim the foregoing as my own, I have hereto affixed my signature in the presence of two witnesses.
